UNITED STATES PATENT OFFICE.

HENRY E. LEPPERT, OF NEW BRITAIN, CONNECTICUT, ASSIGNOR TO THE TRUMBULL ELECTRIC MFG. CO., OF PLAINVILLE, CONNECTICUT, A CORPORATION OF CONNECTICUT.

ELECTRIC SWITCH.

1,381,568.

Specification of Letters Patent. Patented June 14, 1921.

Application filed December 11, 1920. Serial No. 429,908.

To all whom it may concern:

Be it known that I, HENRY E. LEPPERT, a citizen of the United States of America, residing at New Britain, Connecticut, have 5 invented a new and useful Electric Switch, of which the following is a specification.

My invention relates particularly to snap switches of the so-called oscillating type, and the main object is to provide a simple 10 but reliable construction which can be readily assembled without straining the parts. Another object is to provide a construction which is durable and yet easy to operate with a quick snap action.

15 In the preferred form of the invention the oscillating contact member is adapted to be operated by two push buttons, but it will be obvious that the invention is not limited to such a construction. It should 20 also be understood that the invention is equally applicable to single pole or double pole switches, and to single break or double break contacts.

25 The improvements relate particularly to the construction and arrangement of the operating mechanism.

Figure 1 is a side view of a switch embodying the improvements of my invention, part of the insulating receptacle being 30 broken away so as to reveal the interior mechanism;

Fig. 2 is a side view and partial section of the operating mechanism;

Fig. 3 is an end view and partial trans- 35 verse section of the operative mechanism on a larger scale;

Fig. 4 is a perspective view of the supporting frame; and

40 Fig. 5 is a perspective view of the oscillating carrier.

The parts are preferably mounted in an insulating receptacle or body 6 of any suitable construction. One or more contacts, such as 7, of suitable character are mounted 45 within the receptacle and adapted to be engaged by corresponding oscillating contact members, such as 8.

The contact member is suitably secured 50 to a U-shaped carrier 9, which is supported by the frame 10 inside the receptacle. The rocker 11 has a cross piece 12 secured to it and provided with projecting pins 13, which have bearings in the holes 14 in the opposite sides of the frame 10. The cross piece

12 also has stop pins 15 which project into 55 the slots 16, so as to limit the swing of the rocker and cross piece. A guide rod 17, loosely connected with the lower end of the cross piece 12 and projecting through the bottom of the carrier 9, supports a 60 spring 18 which presses against the shoulder 19 and against the bottom of the carrier 9, tending to hold the parts in position, so as to throw the carrier and contact member with a snap action. The shoulders 20—20 65 serve as stops for the carrier 9. In the particular form shown push buttons 21—21 are connected in a suitable manner with the opposite ends of the rocker 11.

To operate the switch from the position 70 shown in Fig. 1 the right-hand push button is depressed, so as to rock the arm 11 about the axis of the projecting pins 13 and tilt the cross piece 12 so as to push the upper end of the guide rod 17 to the left, as 75 viewed in the drawing. This compresses the spring 18 until the point of connection between the cross piece 12 and the rod 17 reaches the plane of the centers of the bearings of the projecting pins 13 and the axis 80 of the carrier 9. Further depression of the right-hand push button 21 results in the spring instantly snapping the carrier and switch contact to the other side.

The frame 10 is provided with bearing 85 lugs 22 stamped outwardly from the sides thereof, and the sheared edge forming the bearing surface is shaped cylindrically on the surface facing toward the bearings 14. The carrier 9 is provided with semi-annular 90 projections 23, adapted to engage the bearings 22. The projecting bearings 23 are preferably formed by piercing holes 24 and drawing part of the metal inwardly, as shown, to form the bearing surface for co-action with the lugs 22. By this method of construction it is possible to provide smooth bearing surfaces at a minimum cost. It also provides a maximum strength for a 95 given amount of metal.

I also prefer to so shape and proportion the parts that when they are assembled the outer faces of the bearing lugs 22 project slightly into the openings 24, as shown in Fig. 3.

100 It will be seen from the foregoing that the carrier can be readily assembled on the frame by simply slipping it into position

before the frame is secured in the insulating receptacle. By having the bearing projections 23 made semi-annular, it is not necessary to strain the sides of the carrier 5 when assembling the parts. By making the width of the frame from the outer face of one of the lugs 22 to the outer face of the opposite lug slightly greater than the distance between the inner faces of the side 10 arms of the carrier 9, there is a slight springing of one of the parts when assembling them, so that the bearing lugs 22 snap into the recesses 24 and hold the parts loosely together, and thus facilitate the 15 other assembling operations.

I claim:

1. In an electric switch, a supporting frame having oppositely disposed bearing lugs, a U-shaped carrier having semi-annular bearing projections engaging said lugs, and means for operating said carrier with a snap action.
2. In an electric switch, a U-shaped frame, a rocker hinged thereto, a U-shaped contact carrier embracing said frame, said frame having outwardly-projecting bearings and said carrier having inwardly-projecting semi-cylindrical bearings co-acting therewith, and a spring holding said carrier in place.
3. In an electric switch, supporting members having outwardly-projecting lugs, a U-shaped carrier having inwardly-projecting bearings extending around only a part of each lug and having openings for receiving the outer faces of said lugs, and a spring-pressed means for oscillating said carrier.
4. In an electric switch, supporting members having outwardly-projecting lugs, a 40 carrier having recesses with semi-cylindrical bearing projections engaging said lugs, and

spring pressed means for operating said carrier.

5. In an electric switch, a U-shaped frame having outwardly projecting lugs, a U-shaped contact carrier having inwardly-projecting semi-cylindrical bearings engaging said lugs, a rocker, a cross piece secured thereto and pivoted in said frame, a guide rod connecting said cross piece and said carrier, and a spring on said rod.

6. In an electric switch, a frame having lugs pressed outwardly from the opposite sides thereof and forming curved bearings, a rocker pivotally supported by said frame, a U-shaped carrier having openings in its side arms to receive the outer faces of said lugs and having curved bearing projections pressed inwardly around one edge only of said openings and engaging said lugs, and a compression spring interposed between said rocker and said carrier.

7. In a switch, a frame having lugs pressed outwardly from opposite sides thereof, a carrier having openings to receive said lugs and semi-cylindrical bearing flanges engaging said lugs and spacing said carrier from the sides of said frame, a rocker pivoted to said frame, and a spring connecting said rocker and said carrier.

8. In an electric switch, a supporting member, a carrier, one of said members having a lug stamped therefrom and providing a cylindrically shaped sheared edge bearing surface, the other of said members having a hole 75 pierced therein and part of the metal drawn from the member and forming a semi-cylindrical drawn metal bearing surface for co-action with the sheared edge bearing surface of the lug aforesaid, and means for operating said carrier.

HENRY E. LEPPERT.
